B. R. WATSON,
SAW HANDLE,
APPLICATION FILED OCT. 7, 1919.

1,383,503.

Patented July 5, 1921.

UNITED STATES PATENT OFFICE.

BAZEL R. WATSON, OF EVERETT, WASHINGTON.

SAW-HANDLE.

1,383,503.

Specification of Letters Patent.

Patented July 5, 1921.

Application filed October 7, 1919. Serial No. 328,959.

To all whom it may concern:

Be it known that I, BAZEL R. WATSON, a citizen of the United States, residing at Everett, in the county of Snohomish and State of Washington, have invented certain new and useful Improvements in Saw-Handles, of which the following is a specification.

This invention relates to saw handles and 10 is an improvement on the construction shown in the United States Patent No. 981,100, granted to C. M. Minton, January 10, 1911.

It has been found that a saw constructed 15 in accordance with the above mentioned patent cannot be manufactured cheaply enough to meet with commercial favor when placed upon the market and therefore one of the 20 principal objects of this invention is to improve and simplify the construction of this saw handle so that the same may be successfully and economically manufactured.

A further object of this invention is to 25 improve the construction of the saw handle shown in the above mentioned patent whereby the several parts of the handle may be conveniently assembled and reliably attached to a saw.

A further object of the invention is to 30 provide a saw handle having novel means for securing the handle in an adjusted position with relation to the blade whereby the blade may be positioned at any desired angle with relation to the handle.

35 Other objects and advantages of the invention will be apparent during the course of the following description.

In the accompanying drawing forming a part of this application and in which like 40 numerals are employed to designate like parts throughout the same,

Figure 1 is a perspective view of the saw handle attached to a saw blade,

Fig. 2 is a vertical section through the 45 handle,

Fig. 3 is a group perspective of a locking device embodied in the invention.

In the drawing wherein for the purpose 50 of illustration is shown a preferred embodiment of my invention, the numeral 5 designates a casing or housing including longitudinally aligned sockets 6 and 7 and a transversely extending tubular extension 8. A relatively stationary handle 9 is secured 55 within the socket 7 by a transversely extending rivet 10,

As in the case of the aforementioned patent a guard or shield 11 is provided with a rearwardly extending nipple 12 having an interiorly screw threaded portion 13 receiving and having engagement with a threaded sleeve 14. A bolt 15 slidably extends through the sleeve 14 and nipple 12 and is provided with a head 16 which engages an annular shoulder 17 formed in the casing 60 5. The rear end of the sleeve 14 engages the head 16 and is limited in its rearward movement thereby. The forward portion of the bolt 15 is bifurcated to provide arms 18 between which a saw blade 19 is adapted to 65 be arranged. A locking pin or other retaining element 20 is passed through the arms 18 and the saw blade 19 for securing the blade 19 to the bolt 15. The front face of the guard 11 is provided with a longitudinally extending groove 21 receiving the rear end portion of the blade 19. The lower end portion of the guard 11 is bent forwardly to provide an arm 22 adapted to extend over the rearmost teeth of the blade 70 75 80 for preventing said teeth from cutting into the flesh.

As in the case of the Minton patent on which this invention is an improvement, rotation of the sleeve 14 within the nipple 12 85 forces the guard 11 into rigid engagement with the blade and thereby secures the same in an adjusted position. When it is desired to release the guard from contact with the blade preparatory to removing the blade, the 90 sleeve 14 is rotated in the opposite direction for drawing the guard 11 rearwardly from the blade.

For the purpose of locking the sleeve 14 to the handle whereby the sleeve may be 95 rotated with the handle I have provided a locking loop 23 which is adapted to surround the rear end portion of the sleeve and be brought into locking engagement with the same. The loop 23 is provided with an 100 integral exteriorly screw threaded shank 24 adapted to be threaded into a sleeve 25. As illustrated in Fig. 2, the sleeve 25 has its rear end portion extended centrally within the forward end portion of a rotatable handle 26 and is rigidly secured to the handle by a transversely extending rivet 27. A locking collar 28 is slidably arranged on the shank 24 and is provided with pairs of 105 downwardly extending teeth 29 adapted to 110 bite into the sleeve 14 and coact with the loop 23 in preventing rotation of the sleeve

14 with relation to the loop 23. The forward end portion of the collar 28 is recessed, as indicated at 30, between the pairs of teeth 29 so that the teeth will not be prevented 5 from engaging the sleeve by the adjacent portion of the loop 23. As illustrated in Fig. 2 the forward end portion of the exteriorly screw threaded sleeve 25 is extended beyond the handle 26 and engages the 10 rear end portion of the locking collar 28 for forcing the teeth of the same into rigid engagement with the sleeve 14. As the locking loop 23 is drawn upwardly into locking engagement with the adjacent portion of 15 the sleeve 14, the locking collar 28 is drawn downwardly into locking engagement with the opposite side of the sleeve whereby the sleeve 14 is rigidly clamped to the handle. A coiled spring 31 is arranged about the 20 forward portion of the sleeve 25 and is confined between the forward end of the handle 26 and the locking collar 28. The coiled spring 31 is adapted to retain the collar 28 in position when the handle 26 is not tightened. Specifically the spring 31 prevents the teeth 29 from riding up onto the adjacent portion of the loop 23.

In assembling my improved handle, the locking loop 23 and associated elements are 30 arranged within the housing 5 and the sleeve 14 is then passed through the locking loop 23. The nipple 12 is then engaged with the sleeve 14 preparatory to attaching the blade 19 to the forward portion of the 35 bolt 15. The loop 23 and the collar 29 are now brought into locking engagement with the sleeve 14 by a proper rotation of the handle 26. By revolving the handle 26 about the axis of the bolt 15, the guard 11 40 is forced into locking engagement with the rear end of the blade.

When it is desired to adjust the handle at an angle to the blade, the section 26 may be loosened slightly to release the locking 45 connection with the sleeve 14 and the handle may then be rotated to the desired degree. When the handle has been positioned as desired, the section 26 is again rotated to bring the collar 28 and the loop 23 into locking 50 engagement with the sleeve 14.

In constructing the locking device as set forth above the necessity of threading the socket 6 has been avoided and the circumferential teeth on the sleeve 14 have been 55 made unnecessary thereby reducing the cost of the sleeve. The plug cap 26 of the Minton structure has been eliminated. The T-shaped housing of the present device is entirely unobstructed throughout its extent, 60 there being no webs extending across and closing the axially alined branches of the housing, and no part of the housing is exteriorly threaded so that the cost of the housing is less than the cost of the housing 65 employed in the patented device. There is

no upsetting operation needed in producing any part of my structure nor in assembling the parts after they are produced. The locking pawl employed in the Minton structure is dispensed with as well as the web in 70 which said pawl plays and as a result, the cost of the housing is materially reduced.

It is to be understood that the form of the invention herewith described and shown is to be taken as a preferred embodiment of 75 the same and that such minor changes in the construction of parts may be made as will remain within the spirit of the invention and the scope of what is claimed.

Having thus described the invention, what 80 is claimed as new is:

1. A locking device for saw handles including a housing, the interior of which is unobstructed throughout, a guard having a tubular nipple arranged in said housing, a sleeve rotatable within said housing and connected to said nipple to adjust the same, a fastener extending through said sleeve, said nipple, and said guard to secure the saw blade, a locking loop arranged within the 90 housing and engaging one end of said sleeve and provided with an exteriorly screw-threaded shank, the opposed surfaces of the loop and the sleeve being smooth, a locking collar slidably mounted on said shank and 95 having pairs of teeth on opposite sides of said loop adapted to engage the sleeve, a handle having one end portion rotatably arranged within the housing, an interiorly screw-threaded sleeve fixed concentrically to and 100 projecting from said handle and having threaded engagement with said shank, said handle being adapted to be rotated for simultaneously engaging the teeth of said collar and said loop with said first-named sleeve, 105 and a coiled spring confined between the opposed ends of said locking collar and said handle around the sleeve projecting from the handle for securing the collar in position. 110

2. A saw handle including a T-shaped housing, the interior of which is entirely unobstructed, a guard having a nipple disposed within the lateral branch of the housing, a fastening member extending through 115 the sleeve to secure the saw blade and having a head at its outer end at the exterior of the housing to cover the outer end of said sleeve, a locking loop surrounding one end of said sleeve and provided with a threaded 120 shank disposed within one longitudinal branch of the housing, the opposed surfaces of the loop and sleeve being smooth, a locking collar encircling said shank and provided with pairs of forwardly extending 125 teeth adapted to engage said sleeve at opposite sides of the locking loop, a handle rotatably mounted at the end of said longitudinal branch of the housing, a second sleeve fixed to said handle and extending concen- 130

trically from the same within said branch and having threaded engagement with said shank, the forward end portion of said sleeve being arranged to abut the rear end 5 of said collar for forcing the teeth of the same into engagement about said first-named sleeve, and a coiled spring surrounding the extended portion of said threaded sleeve and confined between the adjacent ends of said 10 handle and said locking collar to retain the teeth of said collar in engagement with the adjacent portion of said first-named sleeve.

3. In a saw handle, the combination of a T-shaped housing the interior of which is 15 unobstructed throughout, a guard constructed to engage the end of a saw blade and having a nipple extending within the lateral branch of the housing, a sleeve disposed within said branch of the housing and operatively engaging said nipple whereby to 20 move the guard into or out of engagement with the saw blade, a fastening member extending through said sleeve to secure the blade, a handle member fixed to one longitudinal branch of the housing, a second handle member rotatably fitted to the end of the other longitudinal branch of the housing, and a telescopic locking device disposed 25 within the housing and connecting said second handle member and the outer end portion of said sleeve.

In testimony whereof I affix my signature.

BAZEL R. WATSON. [L.S.]
